UNITED STATES PATENT OFFICE.

AXEL A. STROM, OF AUSTIN, ILLINOIS.

CLIP FOR RAILROAD-SWITCH PIVOTAL TIE-RODS.

SPECIFICATION forming part of Letters Patent No. 394,943, dated December 18, 1888.

Application filed September 4, 1888. Serial No. 284,544. (No model.)

To all whom it may concern:

Be it known that I, AXEL A. STROM, a citizen of the United States, residing at Austin, in the county of Cook and State of Illinois, have invented a new and useful Improvement 5 in Clips for Railroad-Switch Pivotal Tie-Rods, of which the following is a specification.

In some railroad-switches the switch-rails 10 are connected by stiff or jointless tie-rods, to cause their simultaneous movement in adjusting them. In others the tie-rods are connected for the purpose at their extremities flexibly to the opposing sides of the switch-rails by pivoting the ends of the rods in clips, which are rigidly secured to the rails.

My improvement relates to the last-named construction.

As hitherto formed, so far at least as one 20 construction known to me is concerned, the clips affording the medium for pivotally connecting the tie-rods at their opposite ends to the switch-rails have comprised, each, a cross-bar to be secured to the web of a rail, and to 25 the center of which, at one side, is connected, by welding, a bent stem, which enters toward its extremity between the prongs of an end or head of the tie-rod, which has thus to be bifurcated at opposite ends to permit the 30 application to it of the clips, and a bolt passed through perforations in each bifurcated head and through a perforation in the stem of a clip thus embraced between the prongs at 35 an end of the tie-rod connects the latter pivotally with the switch-rails. This construction of clip, for the purpose named, is objectionable, because of the expense involved in its manufacture, and because of its liability to break with use, the connection by welding 40 of the cross-bar and stem not being sufficiently strong to resist the strain incident to the use of the device.

The objects of my improvements are to provide a clip for the purpose stated, which shall 45 be equally strong throughout all its parts, so far as it may be, by being stamped out of a single piece of metal to form the blank, and which shall involve comparatively little expense in its manufacture, and materially reduce 50 the cost of manufacture of the tie-rod by avoiding the expense of construction in-

curred by providing bifurcated heads at its extremities.

My invention consists in the general construction of my improved clip, and it also 55 consists in details of construction and combinations of parts.

In the accompanying drawings, Figure 1 shows a perspective view representing my improved clip. Fig. 2 shows a cross-section of 60 a switch-rail having my improved clip, presented in end elevation, applied to it, and part of a tie-rod pivotally connected with the clip. Fig. 3 is a plan view of a blank from which the clip may be formed, and which is 65 integral, being stamped out of a single piece of metal.

A is the clip formed from a blank, B, stamped out of a plate of steel to produce the body portion *r*, short arms *q*, and longer arms, 70 *p* and *p'*, the latter being substantially at right angles to each arm *q*, and the arm *p* being somewhat longer than the arm *p'*, and each of the arms should be perforated, as shown, near its extremity. If desired, the 75 arms *p* and *p'* may have the rectangular form shown of the arms *q*, though it is preferred that they taper somewhat, as illustrated, toward their ends, and that the latter be rounded. The shapes of the arms, however, 80 are not material, and may be varied at pleasure without departing from my invention.

To produce the clip from the blank B, the arms *p* and *p'* are bent from, or from near, their junction with the body portion toward each 85 other, to cause them to converge, as shown, and the end portions containing the perforations are bent to assume right-angular positions with relation to the body *r* and form lips *n* and *n'*, the perforations in which coincide with each other, a space being provided 90 between the lips sufficiently wide to admit a perforated end of the tie-rod C, by bending the lip *n'* slightly to offset it, as shown:

A clip, A, should be provided for each tie-rod at each end of the latter, with which the clip is pivotally connected by means of a 95 suitable bolt, *m*, and the clips for each tie-rod are firmly secured to the opposing faces of the webs of the switch-rails, as by means of 100 bolts *l* passed through the openings in the arms *q* and in the webs of the rails.

The arm q may be omitted, when the clip could be secured to the rail at its body portion r , though this construction is not so desirable as that shown.

5 Inspection of Figs. 1 and 2 of the drawings will show that the arms p and p' do not extend from the opposite edges of the body portion r , as they would were they merely bent toward each other from the blank, but that 10 they extend from the face of the body portion near the opposite edges thereof, which is caused by swaging them in the bending operation. It is preferred to make the clip in the form illustrated, because the body portion r should be of a width corresponding with that of the rail-web, when, if the arms p and p' were merely bent from the edge of the body portion r , their thickness would prevent the latter from fitting against the web of the 15 rail, while by swaging them as described this is avoided.

What I claim as new, and desire to secure by Letters Patent, is—

1. In a blank for a clip for use in pivotally connecting a tie-rod with a switch-rail, a single piece of metal having a body portion, r , and arms p and p' extending transversely therefrom, substantially as described.

2. A blank, B, for a clip for use in pivotally connecting a tie-rod with a switch-rail, comprising a single piece of metal forming a body portion, r , arms q , and arms p and p' , substantially as described.

3. A metal clip for affording pivotal connection of a tie-rod with a switch-rail, having 35 a body portion, r , provided with bent arms p and p' extending from it, substantially as described.

4. A metal clip for affording pivotal connection of a tie-rod with a switch-rail, comprising 40 a body portion, r , having arms q extending from it, and bent arms p and p' extending from the body portion between the arms q , substantially as described.

5. A clip for affording pivotal connection of 45 a tie-rod with a switch-rail and formed of a single piece of metal and comprising a body portion, r , having arms q extending from it, and bent arms p and p' extending from the body portion between the arms q and bent toward 50 their end to form lips extending transversely to the body portion, substantially as described.

6. The combination of a metal clip, A, comprising a body portion, r , having arms q extending from it, bent arms p and p' extending toward each other from the body portion between the arms q , and a tie-rod, C, fitting near one end between the ends of the arms p and p' and pivotally connected therewith, substantially as described.
